UNITED STATES PATENT OFFICE.

JOHN F. KELLY, OF HOBOKEN, NEW JERSEY, ASSIGNOR TO THE UNITED STATES ELECTRIC LIGHTING COMPANY, OF NEW YORK, N. Y.

ELECTRICAL-CURRENT INDICATOR.

SPECIFICATION forming part of Letters Patent No. 372,851, dated November 8, 1887.

Application filed December 1, 1886. Serial No. 220,364. (No model.)

To all whom it may concern:

Be it known that I, JOHN F. KELLY, a citizen of the United States, residing at Hoboken, in the county of Hudson and State of New Jersey, have invented certain new and useful Improvements in Current-Indicators, of which the following is a specification, reference being had to the drawings accompanying and forming a part of the same.

10 This invention is an improvement in that class of electrical instruments which are used for indicating the amount or strength of currents, and is designed for use as an ammeter. The invention consists in improvements in the 15 construction of the instrument, which render it more durable and generally more efficient and practicable than others of its class.

Said improvements consist, first, in the employment, in combination with a field-magnet, 20 of a soft-iron armature-plate pivoted in proper relation to said magnet and divided up by slots into numerous parts, by means of which the direction of the lines of force is determined and the effects of residual magnetism reduced to a 25 minimum; and, second, in a peculiar and novel construction and adaptation of the several parts of the apparatus that renders the same more serviceable for use with circuits carrying heavy currents.

30 These improvements are illustrated in the accompanying drawings, in which—

Figure 1 is a side elevation of the instrument with the armature and one of its supports omitted; Fig. 2, a vertical broken section of the same; Fig. 3, a cross-section of Fig. 2, taken just below the magnet-cores; and Fig. 4, a side elevation of the armature and indicator-needle.

The instrument is secured to a vertical support 40 by means of brackets A A'. To the upper plate or bracket, A, the cores B C are secured by screws c, which pass through the conductors surrounding the cores and are insulated from them. The cores are flat iron plates built up of a number of thin strips laid one upon another and bound together by rods and screws d, passing through holes in the strips near their ends. These cores are surrounded by the coils, which in the present instance consist 45 of two flat copper bands, D E. Each one of these bands is bent so as to fit over the cores,

as shown in Fig. 2. They are placed over the cores near their ends, and are connected together in series and so as to co-operate in magnetizing the cores by a cross-strip, F, clamped 55 to the ends of the bands, as shown in Fig. 3. The ends of the bands D E that form the terminals of the instrument are provided with sockets of metal G G, which are either united to the bands or cast in one piece with them. 60

To the bands D E are secured cross-bars H, one of which is shown in Fig. 1. These bars are insulated from the bands, and are provided with bosses K, through which pass pivoting-screws L. By means of these screws the armature and pointer are supported between the 55 cores.

The armature is a flat soft-iron plate or bar, M, pivoted at its center and divided up into a number of parts or sections by the slots N. The 70 object of this is to determine the direction of the lines of force and to weaken the residual magnetism, so that it may not interfere with the proper working of the instrument. The same result may be obtained by dividing up the 75 said plate in other similar and well-known ways. To the plate itself, or to a short spindle passing through it, is secured a pointer, O, for which a proper scale, P, is provided, and an adjustable weighted arm, R, serving as a counterpoise. 80

The plate, pointer, and counterpoise are set at different angles to each other in the same or parallel planes. The normal position of the armature is with its longer dimension nearly 85 at right angles to the line joining the poles of the cores. When in this position, the pointer is on the zero-mark of the scale; but the armature will be more or less shifted by magnetic attraction, its deflection increasing with the 90 strength of the current acting on the cores, so that the pointer will indicate by its position the strength of current flowing.

The above-described apparatus forms a very sensitive and accurate current-indicator, and 95 has the advantage of not requiring a permanently-magnetized armature. When once adjusted, therefore, it requires no further attention, as the opposing force—gravity—will be always practically the same. The bars constituting the coils in this case may be insulated 100 from the cores in any convenient manner, and

may vary in size and number. In small instruments the ordinary coils will be preferable.

What I now claim is—

1. In a current-indicator, an armature supported in a magnetic field formed by magnetic plates surrounded by coils or bars, and consisting of a centrally-pivoted soft-iron plate slotted or divided in substantially the manner set forth.

2. The combination, in a current-indicator, 10 with a pivoted iron plate slotted or divided up

into a number of parts, of iron cores on opposite sides of the plate, and copper bands bent so as to surround the sides and upper edges of the cores, and provided with sockets or means for connecting them with the wires of a circuit, as 15 herein set forth.

JOHN F. KELLY.
